UNITED STATES PATENT OFFICE

120,905

DESIGN FOR A COMBINATION DISK RECORD DISPLAY AND SALES COUNTER

Aaron Bitter, Long Island City, N. Y.

Application March 4, 1940, Serial No. 90,671

Term of patent 7 years

To all whom it may concern:

Be it known that I, Aaron Bitter, a citizen of the United States, residing at Long Island city, in the county of Queens and State of New York, have invented a new, original, and ornamental Design for a Combination Disk Record Display and Sales Counter, of which the following is a specification, reference being had to the accompanying drawings, forming part thereof.

Figure 1 is a front elevational view of a combination disk record display and sales counter, showing my new design.

Figure 2 is a top plan view thereof.

Figure 3 is a rear elevational view.

Figure 4 is a vertical transverse sectional view taken substantially on the line 4—4 of Figure 3, and

Figure 5 is an end elevational view.

I claim:

The ornamental design for a combination disk record display and sales counter, as shown.

AARON BITTER.
